UNITED STATES PATENT OFFICE.

ANTOINE PADOUÉ FILIPPI, OF PARIS, FRANCE.

SCREW-PROPELLER.

1,078,270.

Specification of Letters Patent. Patented Nov. 11, 1913.

Application filed March 24, 1911. Serial No. 616,712.

To all whom it may concern:

Be it known that I, ANTOINE PADOUÉ FILIPPI, a citizen of the French Republic, residing at 132 Avenue du Maine, Paris, France, have invented new and useful Improvements in Screw-Propellers, of which the following is a specification.

The present invention relates to a screw propeller with two or more blades.

According to this invention the pitch of the blades increases from the boss toward the end and from the leading edge toward the trailing edge.

Each blade of the screw is combined near the boss with a plane that forms a determined angle with the blade. This plane is found on each of the faces of the blade. The plane arranged on the back face is intended to contribute to the retention or hold; the plane arranged on the front face and on the side of the leading edge is intended to reduce the velocity of the small streams of water normal to the propeller by diverting these small streams of water so as to throw them in front of the leading edge. It will thus be seen that each blade is provided at the bottom, in the front part, with a diverting surface, and at the back part with a retaining surface.

The purpose intended is to relieve the front surface of the propeller and to have as much water as possible on the back surface.

In the accompanying drawings several views are given illustrating by way of example two different methods of carrying out the present invention.

Figure 1 is a plan of the front face of a propeller with two blades. Fig. 2 is a plan of the back face. Fig. 3 is a side elevation, the right hand part of the figure representing the back face, and the left hand part representing the front face of the blades. Fig. 4 is an end elevation of the screw, the direction of rotation of the propeller being toward the left hand side of the figure. Fig. 5 is a section through I—I in Fig. 1, and Fig. 6 a section through II—II in the same figure. Figs. 7, 8 and 9 are respectively a plan, a side elevation, and an end elevation illustrating another method of constructing the same propeller. Fig. 10 is a diagrammatic

figure showing a plurality of sectional views of the device.

As will be seen from the drawings each blade 1 has on the side of the trailing edge on its front face a plane 2 forming a diverting surface which facilitates the arrival of the water under the other blade 1'. This central diverting surface, by reducing, as has been mentioned, the velocity of the small liquid streams, enables the leading edge 3' of the surface 1' to meet and to take support on them. On this back face (Figs. 2 and 5) the retention surface 4 prevents the small streams of water which are in this area and which are subjected to less action of the centrifugal force in consequence of their coming nearer to the center, from escaping by the issue edge 5 of the blade 1, and keeps always full of water, the area partially limited by the surface of the blade 1 between the end 6 of that blade and the axis 7 of the boss.

The planes of the two blades intersect each other as shown by the lines of intersection a—b—a'—b' which, if the surfaces are planes, may be rectilineal, but may have any other form according to the nature of the surfaces adopted. Thus, in Figs. 7, 8 and 9, the surfaces adopted being approximately parabolic or ellipsoidal, the intersections of these surfaces give the curve which is shown in the drawings. It is quite evident that this arrangement of the blades is independent of the angle which they form in relation to one another in any plane whatever, or of the angle which they form with the shaft of the screw. The blade may obviously have any external contour whatever. These means together enable the mean pitch of the screw to be reduced, the screw to be turned very quickly while assuring the retention of the water on the working surface, and the relieving of the blade on the front surface, the result of which is very great efficiency.

What I claim and desire to secure by Letters Patent is:—

A screw propeller comprising a plurality of blades, in each of which the pitch increases from the hub to the end, and from the leading edge to the trailing edge, the front face of each blade being provided with an inclined surface adjacent its trailing

edge and adjacent the hub of the propeller, the rear face of each blade being provided with an inclined surface adjacent the hub of the propeller, the planes of said inclined surfaces intersecting one another and passing through the shaft of the propeller, such diverting surfaces forming suitable angles with the blades.

In testimony whereof I have signed my name to this specification in the presence of 10 two subscribing witnesses.

ANTOINE PADOUE FILIPPI.
